INVENTOR.

UNITED STATES PATENT OFFICE.

GEORGE WILLIS PEEK, OF SAN FRANCISCO, CALIFORNIA.

NARROW-DOORWAY WALL-BED.

1,383,420.

Specification of Letters Patent. Patented July 5, 1921.

Application filed May 29, 1918. Serial No. 238,594.

To all whom it may concern:

Be it known that I, GEORGE WILLIS PEEK, a citizen of the United States, and a resident of the city and county of San Francisco, State of California, have invented certain new and useful Improvements in Narrow-Doorway Wall-Beds, of which the following is a specification.

My present invention relates to improvements in converting common metal or wood bedsteads into collapsible beds, adapted to be shifted through a narrow doorway and concealed in a closet when not in use, such improvements being of a nature as to enable me to fold or unfold the parts without modifying the factory or standard design of the head or foot sections of the bedstead.

Another object of the invention is to provide a wall bed that can be readily detached and removed to and used as a bed in any part of the room without a wall connection. Ordinary wall beds are affixed to the building and can not be detached and used as common beds in other rooms, without first installing to a wall. I also provide superior and simple means for moving and guiding the bed through the doorway and out fully into the room to be lowered into position for use.

The present application applies principally to a bed frame balancing mechanism; and a vertical supporting mechanism for maintaining the up-ending bed-frame in a vertical position as required; which are applicable in construction of a certain wall-bed of my invention Letters Patent No. 1,200,945, patented October 10, 1916. Certain of the features of invention disclosed in the present case are also disclosed in the aforesaid Letters Patent. However, in the particular construction shown in the drawings in this application, there are also incorporated certain other features not shown or described in the aforesaid Letters Patent.

My invention consists of certain novel features of construction, combination and arrangements of parts, as will be hereinafter described in detail and particularly set forth in the appended claims, reference being had to the accompanying drawings, in which:

Figure 1 is a perspective of the wall-bed embodying the principles of my invention.

Fig. 2 is a diagrammatic plan of a parti-

tion and adjoining closet showing the device as stored in the closet (in dotted lines) and as extended through the closet doorway. 55

Fig. 3 is an enlarged fragmentary perspective showing the details of the balancing mechanism, pivotally connected with a portion of a side rail of the bed-frame.

Fig. 4 is an enlarged fragmentary side view showing the bed-frame as up-ended and the head-board in contact with the upper transverse bar of the counterbalancing mechanism.

Similar characters of reference refer to similar parts throughout the several views. 65

The head and foot sections 1 and 2 may be constructed in accordance with any design or pattern, it being unnecessary to modify the style or pattern of those parts to enable my improvements to be used in connection therewith. The bed-frame 3 may be constructed of angle iron, but if desired, the side rails to this bed-frame may be made of metal tubing. The head and foot frames 1 and 2 and this last mentioned bed-frame 3 are each complete within itself, said bed-frame consisting of side and end cross rails, which are properly fastened together. In connection with this frame, the inner cross rail is attached by means of screws or bolts to a suitable head-board 10, said head-board being reinforced with braces 11, and is of a suitable width to extend over and to ride upon transverse bar 19 while up-ending frame 3 is being adjusted to a vertical position and also to prevent the tilting of said frame 3 rearward beyond a vertical line with its transverse axis. 75 80 85

In connection with head section frame 1, I employ three U-shaped supports 4-5 and 6 which are preferably attached to the posts of said frame 1, by means of suitable bolts or rivets 7, the two lower supports 5 and 6 have forward extensions, rigidly connected together with vertical members 8 and cross-members 9; this construction provides suitable supporting brackets within which are pivotally mounted with horizontal pivots 12 bed-frame 3, thus connected said frame 3 is movable in a vertical arc, then to a horizontal position for use. In order to counterbalance the movement of said bed-frame 3 when it may be folded up or unfolded, a toggle-joint mechanism has been provided, consisting of upper and lower links 14 and 90 95 100

15. Link 14 is pivotally connected adjacent with the inner end of side rails in bed-frame 3 as shown at 13 and links 15 in said toggle-joints are pivotally connected with U-shaped 5 supporting brackets 6 as shown at 17.

Rigidly connected to the sides of links 15, extending upward to a required height are brackets 18, said brackets 18 are rigidly attached to a transverse angle bar 19 to 10 which are looped at each end of said bar 19

a battery of coiled springs 20. The lower ends of said springs 20 are connected with transverse tie bar 21, said transverse bar 21 being rigidly attached at each end with the 15 extended ends of supports 6 and members 8, and as said springs 20 are thus associated with the tie bar 21 and with the movable transverse bracket bar 19, said springs are placed under tension when the bed-frame 3

20 is lowered and by this means assist in raising the bed-frame 3 to an upright position.

My invention furthermore contemplates an automatic interlocking contrivance, controllable by the adjustment of the foot-section 25 frame 2, in a way to positively lock and sustain said section in an upright position—overcoming the possibility of collapsing while same is in use.

In connection with the foot frame section 30 2, I employ links 21 and 22 which are curved or fashioned in a manner to provide suitable supports that may be connected with the outer side of the posts in said foot section 2, and with the outer side of said side rails 35 of bed frame 3 adjacent to the outer end of said frame as shown at 28 and 29. It will be further noted that the links 21 and 22 are pivotally connected with the posts in said foot section 2 and pivotally connected

40 with the bed-frame 3 near its outer end in a manner to enable the foot section 2 to be folded over and upon the bed-frame 3. In order to sustain the bed-frame 3 and prevent it from falling to the floor while the foot

45 frame section 2 is disconnected from said bed-frame, I have provided means in the way of auxiliary legs 26, pivotally connected with the bed-frame sides, as shown at 30, said legs 26 are of a length somewhat shorter

50 than the length of the head and foot sections 1 and 2 in order that said bed legs 26 will not rest upon the floor while bed is in use. Pivotally connected with legs 26 and members 8 are tie links 27, these tie links

55 prevent said legs 26 from folding outward beyond their vertical position should the bed-frame become moved. In order to provide substantial supports and means for interlocking the foot-frame section 2 with the

60 outer end of bed frame 3 while foot section 2 is not folded and is in upright position, I have provided and rigidly attached adjacent with the outer corner of foot cross rail in frame 3, loop-hook shaped brackets 24, and

65 to the inner side of the posts of section 2 are

fixed trunnions 25, said trunnions fitting loosely into openings provided in brackets 24. In order to connect or disconnect the trunnions 25 with or from said brackets 24, while the foot section 2 is being adjusted a slot connection 23 is provided in links 22, as shown in Fig. 1; with this device the bed-frame 3 may be lifted up to unlock or detach the trunnions from the hook supporting brackets.

Attached to the inner wall within the closet adjacent with one side of the opening and at a suitable height from the floor is vertical bracket 31 upon which are counter part supporting and guiding arms 32 pivotally connected by means of pintle 33, said arms being reinforced with brace members 34, said arms being of a suitable length and strength to carry the bed through the opening into the closet, as shown in Fig. 2. Pivotally mounted on the extended ends of said arms 32 with pintle 35 are U-shaped supports 4—5 and 6, thus mounted the bed is ready for use.

When it may be desired to disconnect the bed from the supporting arms and use it elsewhere as a common non-collapsible bed, the bed may be disconnected from said supporting arms 32 by removing pintle 35 which pivotally connects the U-shaped support 4—5 and 6 with said supporting arms, and in order to prevent the bedstead member 1 from collapsing on its pivot 12, with the up-ending bed-frame 3, when so disconnected I have provided means for rigidly connecting together with suitable bolts or catches the outer extension ends of U-shaped supports 5 with the inner side ends of the up-ending frame 3 as shown at 36.

Having thus described the invention what I claim is—

1. In a collapsible bed, the combination with a pivoted up-ending bed-frame, a lower U-shaped bed-stand support having forward extensions, vertical members attached to said extensions, a transverse bar connecting said extensions, a resilient counter-balancing mechanism comprising a toggle-joint connection on opposite side of said up-ending bed-frame and pivotally connected therewith, the lower links on said toggle-joint connections being pivotally attached with and adjacent to the outer corners of said low U-shaped support, lateral extensions on the lower links of said toggle-joints forming brackets, a transverse bar connecting said brackets, tension springs between the oscillating and rigid transverse bars, means for restricting the movement of said up-ending bed-frame beyond a vertical position, said means comprising a transverse head-board engaging with said oscillating transverse bar.

2. In a collapsible bed the combination with a pivoted up-ending bed-frame, of

means for facilitating the up-ending of said bed-frame, said means comprising a toggle-joint mechanism provided with an upper oscillating transverse bar and a lower rigid transverse bar flexibly connected, and means for rigidly sustaining the up-ending bed-frame while said bed-frame assumes a horizontal position, said means comprising locking bolts or stop catches, engaging the inner

end of said up-ending bed-frame with its 10 pivoted bracket supports.

In testimony whereof, I have hereunto set my hand in the presence of two subscribing witnesses.

GEORGE WILLIS PEEK.
